UNITED STATES PATENT OFFICE.

ARTHUR H. PITNEY, OF STAMFORD, CONNECTICUT, ASSIGNOR TO PITNEY-BOWES POSTAGE METER COMPANY, OF STAMFORD, CONNECTICUT, A CORPORATION OF DELAWARE.

DESIGN FOR POSTMARK STAMP.

Application filed May 8, 1924. Serial No. 9,525. Term of patent 14 years.

To all whom it may concern:

Be it known that I, ARTHUR H. PITNEY, a citizen of the United States, residing at Stamford, in the county of Fairfield and State of Connecticut, have invented a new, original, and ornamental Design for Postmark Stamp, as shown in the accompanying drawing, forming part of this specification.

The design consists in the novel and ornamental postmark stamp illustrated in the drawings.

The drawing shows the design for postmark stamp.

I claim:

The ornamental design for postmark stamp substantially as shown.

ARTHUR H. PITNEY.
